UNITED STATES PATENT OFFICE.

FREDERICK C. HENNING, OF CHICAGO, ILLINOIS, ASSIGNOR TO THE MIRACLE ARTIFICIAL ARM CO., OF CHICAGO, ILLINOIS, A CORPORATION OF ILLINOIS.

ARTIFICIAL ARM.

1,366,453.

Specification of Letters Patent. Patented Jan. 25, 1921.

Application filed July 24, 1919. Serial No. 312,987.

To all whom it may concern:

Be it known that I, FREDERICK C. HENNING, a citizen of the United States, residing at Chicago, county of Cook, State of Illinois, have invented a certain new and useful Improvement in Artificial Arms, and declare the following to be a full, clear, and exact description of the same, such as will enable others skilled in the art to which it

10 pertains to make and use the same, reference being had to the accompanying drawings, which form a part of this specification.

My invention has for its object to produce a simple and novel artificial arm comprising 15 upper and lower arm members; together with a simple and novel harness for supporting the arm and permitting it to be moved and flexed very much in the same way as a human arm.

20 The various features of novelty whereby my invention is characterized will herein-after be pointed out with particularity in the claims; but, for a full understanding of my invention and of its object and ad- 25 vantages, reference may be had to the following detailed description taken in connection with the accompanying drawings, wherein:

Figure 1 is a front view of the upper part 30 of a man wearing a device arranged in accordance with the preferred form of my invention;

Fig. 2 is a rear view;

Fig. 3 is a longitudinal axial section, on 35 an enlarged scale, through the arm at the hinge joint;

Fig. 4 is a side view of the arm, the upper end and the hand being omitted; and

Fig. 5 is a section taken approximately on 40 line 5—5 of Fig. 2, through a part of the harness.

Referring to the drawings, 1 and 2 are respectively the upper and lower arm members of an artificial arm; the same being pivotally connected together at the elbow by 45 means of a suitable shaft or pintle, 3. The members 1 and 2 may be of any usual or suitable construction, the upper end of the member 1 being, however, made hollow so as to be capable of receiving the stump of an 50 arm which has been amputated above the elbow.

The arm is flexibly suspended from a saddle, 4, which is adapted to rest upon the 55 shoulder from which the remaining frag-

ment of the human arm extends; the connection between the saddle and the artificial arm being conveniently effected by means of a heavy flexible strap, 5, of leather or other suitable material extending from the saddle 60 down to the top of the upper arm member at the outer side of the latter. Of course it will be understood that the saddle and the connecting member 5 may be made out of a single piece of material if desired. 65

The saddle is secured in place by means of two adjustable straps formed into loops lying in planes approximately at right angles to each other; one of the straps, 6, being comparatively short and passing from 70 the front lower edge of the saddle under the adjacent armpit and back to the rear lower edge of the saddle; and the other strap, 7, being long enough to extend across the chest of the wearer, under the opposite 75 armpit, and across the back of the wearer to the saddle. The straps may conveniently be adjusted by means of buckles, 8 and 9.

It will be seen that by properly proportioning the parts, the straps not only hold 80 the saddle firmly in place on the shoulder but, acting with the saddle, they form a harness by means of which the artificial arm may be drawn snugly up on the upper arm 85 fragment of the wearer without interfering with the freedom of movement of the fragment of the human arm.

The artificial arm may be flexed automatically through the mere movement of the portion of the human arm to which it is connected. To this end I have placed within the artificial arm, at the elbow, a wheel or pulley, 10, which may conveniently be loosely supported on the hinge pin or shaft, 3, as best shown in Fig. 3. A cable, 11, is 95 fastened at its front or lower end to a point in the forearm near the back side thereof and not far from the elbow, as indicated at 12. The cable is then wrapped around the wheel or pulley, 10, and is carried out to the 100 rear side of the upper arm member through a hole, 13, lying at some distance from the elbow. The free upper or outer end of the cable 11 is fastened to an adjustable strap, 14, attached to the saddle 4 at a point which 105 approximately overlies the adjacent shoulder blade. It will be seen that when the arm is swung forward the distance between the hinge axis of the elbow and the point of attachment of the strap 14 with the saddle in- 110

creases and therefore the length of the proportioning part of the cable 11 must be increased. The increase in length of the cable on the outside of the arm can only be obtained by shortening the portion of the cable lying within the arm, namely by causing the forearm to swing from the full line position toward the dotted line position, illustrated in Fig. 3, and thus bring those two parts of the cable which extend from the hole 13 to the periphery of the pulley and from the periphery of the pulley to the point of attachment, 12, more nearly into alignment with each other than they are when the arm is straight. Therefore, when the wearer swings the artificial arm forward there is an automatic flexing of the arm.

Where the opening and closing of the fingers of the artificial hand is controlled by a movement of the shoulder on the opposite side of the body of the wearer, it is desirable that the movement of the arm itself, in swinging about the shoulder joint or the elbow hinge, have no effect on the finger mechanism. The arrangement illustrated possesses this desirable characteristic. The finger mechanism, not shown, is controlled by a suitable rod, 15, extending longitudinally along the outer side of the forearm, 2, a suitable lock or clamp, 16, being provided to lock the rod in any adjusted position. The rod is moved in one direction by means of a cable, 17, passing between two small rollers, 18, carried by a head, 19, on the end of the shaft or pintle, 3, so that whenever the arm is flexed there will be no tendency to lengthen or shorten the cable. The cable is then continued upwardly through suitable guides, 20 and 21, located respectively on the part 5 and the saddle 4; and it is finally connected to an adjustable strap, 21, extending across the back of the wearer and looped at one end underneath the arm and over the shoulder on the opposite side of the body from that on which the artificial arm is located. The adjustability of the strap 22 may be secured by means of a simple buckle, 23.

The guides 20 and 21 are so placed that the cable 17 in passing from the arm over to the back of the wearer, comes as close as may be to the axis about which the arm swings in its ordinary swinging movements from front to back. Therefore, just as in the case of the elbow joint, there is no tendency to shorten the finger-controlling cable

when the arm is swung at the shoulder, because the effect is simply that of bending or partially folding the cable. When it is desired to actuate the finger-controlling cable, this may be done by a simple shrugging motion of the shoulder around which the strap 22 is looped, regardless of the position of the artificial arm and regardless of whether or not the latter be flexed or straight.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. In combination, an artificial arm, a supporting harness for said arm including a saddle adapted to rest upon the shoulder corresponding to the artificial arm, a strap adapted to extend across the back of the wearer and be looped about the opposite shoulder, a controlling cable extending upwardly along the outer side of the arm and connected at its upper end to said strap, and guiding means on said saddle for causing said cable to lie close to the hinge axis about which said arm moves in swinging toward the back or front.

2. In combination, an artificial arm comprising an upper member and a lower member, harness including a part extending across the shoulder of the wearer on the side at which the artificial arm is to be worn, a cable connected at its upper end to said harness back of said shoulder, said cable passing into the interior of said arm on the rear side of the upper member and having its lower end attached to the forearm near the rear side of the latter, and means at the elbow for loosely engaging and deflecting said cable so as to cause that portion lying within the arm to form two sides of the triangle of which the third side is a straight line extending from the point at which the cable enters said arm and the point at which the free end of the cable is attached to the forearm.

In testimony whereof I sign this specification.

FREDERICK C. HENNING.
